CALL DISTRIBUTING SYSTEM

Filed Nov. 1, 1930 2 Sheets-Sheet 2

UNITED STATES PATENT OFFICE

HERBERT W. DRAKE, OF EAST ORANGE, NEW JERSEY, ASSIGNOR TO THE WESTERN UNION TELEGRAPH COMPANY, OF NEW YORK, N. Y., A CORPORATION OF NEW YORK

CALL DISTRIBUTING SYSTEM

Application filed November 1, 1930. Serial No. 492,349.

My invention relates to switchboard call signal apparatus and circuits and particularly to arrangements for facilitating the distribution of outgoing calls.

5 In large central telegraph offices, telegrams arriving from various sources as from the telephone receiving department, commercial receiving office, or branch offices, either by wire or pneumatic tubes for telegraphic transmission, or from distant stations for retransmission or local distribution, are sent to one or more distributing centers at which point they are sorted by routing clerks and routed to the proper telegraph or telephone 10 operating positions. All telegrams passing into or out of the telegraph office pass through the distributing center.

One object of my invention is to provide a means whereby a routing clerk can determine 20 which of a group of operators is working any line known to be busy.

Another object of my invention is to provide a means whereby the routing clerk can signal an operator who is working a busy line 25 that additional traffic is being brought to her so that she will not release her line.

An important feature of my invention is the accomplishment of the above objects with as little change in the present systems as practicable so that it may be incorporated into existing installations.

In accordance with my invention the routing clerk, upon receiving a message to be transmitted over a certain line, can determine 35 from her busy lamps whether or not this particular line is busy. If it is, she presses a push button associated with that line thereby lighting a lamp at the routing center which indicates to the routing clerk the operator who is working on that line. At the same time a lamp is lighted at the operating position working the line in question as a warning to the operator not to release the line.

The various features and objects of my invention will be more fully understood upon reference to the following detailed description taken in connection with the accompanying drawings, while the scope of my invention will be particularly pointed out in the appended claims.

Figure 1 is a diagrammatic view of the circuits and apparatus employed in accordance with my invention.

Figure 2 is a diagrammatic view of the circuits and apparatus at a switchboard including a subscriber's jack, answering lamps, busy lamps and common equipment therefor.

As shown in Figure 2, an individual subscriber's circuit 1 and 2 extends through the terminal strips 3 and through the back contacts and armatures 4 and 5, respectively, of a cut-off relay 6 to the windings of a line relay 7 which is individual to this particular subscriber's line and which is energized by the closing of this circuit when the subscriber lifts the receiver.

The line relay 7 is provided with an armature 8 which at its front contact extends a circuit over the conductor 9 and one of the terminal strips 10 to answering lamps such as 11 and 12 in parallel individual to each subscriber's line and appearing at each operator's position. This circuit extends over the conductor 13 to a pilot relay 14, the opposite terminal of which is connected to the battery 15 and then to ground at 16.

As is well known, when the line relay is energized the answering lamps 11 and 12 are illuminated over the circuit traced above to indicate to the operator or operators which of the subscribers' lines is calling.

It will be noted that the subscribers' lines 1 and 2, in addition to the connection to the line relay 7, are multiplied over the conductors 18 and 19 to the terminals 20 and 21 of a plurality of jacks which are individual to this particular subscriber's line, jack 22 being one of these jacks.

When a call is received over this subscriber's line, as indicated by the operation of lamps 11 and 12, the operator who is to answer the call inserts an operator's plug 25, Figure 1, comprising a sleeve 26 and tip and ring terminals 27 and 28, into the jack 22 individual to the calling subscriber. The tip and ring terminals 27 and 28 are connected to the operator's cord conductors 31 and 32, respectively, the conductor 31 extending to the winding 33 of a repeating coil and the conductor 32 extending through the supervisory relay 100.

34 to the winding 35 of the repeating coil and then through battery 36 to ground 37. The windings 41 and 42 of the repeating coil extend to the operator's head set and talking set 5 over well known circuits which accordingly need not be described here. As will be understood by those skilled in the art, each operator's position may be provided with a plurality of such cord circuits.

10 As will appear more fully hereinafter in the description of the operation of my invention, when the plug 25 is inserted into the jack 22, the circuit for the supervisory relay 34 is energized if/when the subscriber's receiver is removed from the hook switch and it 15 operates its armature 43 to engage its front contact, bypassing a circuit for the supervisory lamp 44. When the supervisory lamp is extinguished in this manner the operator is 20 advised that the talking circuit has been completed.

One terminal of the supervisory lamp 44 is connected to the sleeve 26 which, when the plug thereof is inserted into the jack 22, extends 25 a circuit over the conductor 29 to the cut-off relay 6, the energizing circuit for which is controlled in this manner.

The cut-off relay 6 comprises, in addition to armatures 4 and 5 which control the line 30 relay, an armature 46 which controls a circuit over conductor 47 to busy lamps 48 and 49, one such lamp appearing before each operator's position. The opposite terminals of lamps 48 and 49 are completed over conductor 35 50 and battery 51 to ground at 52. When the plug 25 is inserted into the jack 22 and the relay 6 is energized, the busy lamps 48 and 49 are illuminated, indicating that this particular subscriber's line is now busy and no other operator should seize this line, all of which is 40 well known in the art.

In accordance with my invention, each operator's cord circuit is provided with an extra relay 53, associated with the supervisory 45 equipment, a lamp 54 which is arranged to be controlled by the relay 53, and a push button 55 which is operated by the operator for extinguishing the lamp 54, as will be fully described hereinafter.

50 At each operating position, the circuit of lamp 54 is controlled by the armature 56 of the relay 53. When the relay 53 is energized the lamp 54 is illuminated over a circuit extending from ground at 57 over battery 58 55 and through winding 59 of relay 53, front contact and armature 56, lamp 54, push button 55 to ground at 60. The lamp 54 remains illuminated until the operator breaks the circuit by operating the push button 55.

60 Referring now again to the supervisory lamp 44, it will be noted that the opposite terminal thereof from that which extends to the sleeve 26, is connected through a resistance 61, and winding 62 of relay 53 over conductor 63 to a lamp 64 at the routing

clerk's position, the opposite terminal of the lamp 64 being grounded through battery 65 at 66. The routing clerk's position is provided with a lamp 64 for each operating position.

At the routing clerk's position a busy lamp 70 is provided for each line, each busy lamp 70 being connected in multiple with the other busy lamps of the same line. Associated with each line is a push button 71 and a resistance 72. Each resistance 72 is connected in series with the winding of the cut-off relay 6 of its associated line and each push button 71 is connected across the terminals of its associated resistance 72. An additional battery 73 of a polarity opposite to that of the regular telephone battery is required by the system.

Having described the arrangement and circuits of the apparatus, a detailed description 85 of the operation will now be given.

It will be assumed that no calls have been received and that accordingly the line relays 7 for all of the subscribers are deenergized. If now a subscriber, such as the one 90 connected to the conductors 1 and 2, Figure 2, closes his circuit by lifting his receiver the circuit will extend to the back contact and armature 5, through the winding of the line relay 7 to battery and ground and through 95 the second winding of the relay 7, armature 4 and its back contact and back over the conductor 1 and the relay 7 is energized.

Energization of the line relay 7 operates its armature 8 to engage its front contact 100 and a circuit is completed from ground through the armature 8 and its front contact, conductor 9, through the lamps 11 and 12 in multiple, conductor 13, winding of pilot relay 14 and through battery 15 to ground 105 at 16. The lamps 11 and 12, upon illumination, indicate to all the operators which of the subscribers is calling.

It will now be assumed that one of the operators inserts her plug 25 (Fig. 1) into the jack 22 individual to the calling subscriber. The circuit over the conductors 1 and 2, which was traced as extending through the line relay 7, now also extends over multiple conductors 18 and 19 to the terminals 20 and 21 of the jack 22 and to the tip and ring 27 and 28, respectively, of the plug 25, conductors 31 and 32 through supervisory relay 34 and through the repeating coil windings 33 and 35 to battery 36.

The supervisory relay 34 is energized, bypassing the lamp 44 over a circuit including the resistance 75. The value of resistance 75 is so chosen with respect to resistance 61 that a substantial by-pass circuit for the lamp 44 is provided without seriously affecting the total resistance of this circuit.

A further result of the insertion of plug 25 into the jack 22 is to complete an energizing circuit for the cut-off relay 6 over a cir-

cuit extending from ground through the battery 73, resistance 72, the winding of the cut-off relay 6, conductor 29, jack 22, sleeve 26 of the plug 25, front contact and armature 43, resistances 75 and 61 in series, through the winding 62 of the extra relay 53 over the conductor 63, lamp 64, battery 65 and ground at 66. The current in this circuit is enough to keep the cut-off relay 6 operated but is not sufficient to operate the extra relay 53 nor is it sufficient to light the lamp 64.

The energization of the cut-off relay 6 operates its armatures 4 and 5 from engagement with their back contacts, opening the circuit 15 of the line relay 7. As a result the line relay 7 is deenergized and in turn opens the circuit of the pilot relay 13 at armature 8 which now moves from in engagement with its front contact. As a result of the deenergization of the 20 line relay 7 the answer lamps 11 and 12 are extinguished indicating that the connection to the calling party has been completed.

The energization of the cut-off relay 6 operates its armature 46 into engagement with its 25 front contact thereby closing the circuit for the busy lamps 48 and 49. This circuit extends from ground over the armature 46 and its front contact, conductor 47, busy lamps 48 and 49 in parallel, conductor 50 and 30 through battery 51 to ground at 52. Inasmuch as the busy lamp 70 at the routing clerk's position is connected in multiple with the busy lamps 48 and 49, the lamp 70 will also be illuminated indicating to the routing 35 clerk that the line is busy.

As business is filed at the routing center for transmission over a certain line, the routing clerk can determine from her busy lamps whether or not that particular line is busy. 40 Let it be assumed that a message has just been filed with the routing clerk for transmission over the line illustrated in Figure 1 and that, as above described, this line is busy. The routing clerk, noting that the line is busy, 45 presses the push button 71 associated with this line, thereby short circuiting the resistance 72. As stated above, previous to this action the current in the cut-off relay circuit was enough to keep the cut-off relay 6 operated 50 but not sufficient to operate the extra relay 53 nor was it sufficient to light the lamp 64. Inasmuch as the line is busy, the supervisor's relay 34 is energized thus shunting the supervisory lamp 44, as described above. However, when the routing clerk presses the push 55 button 71 the increased current due to the elimination of the resistance 72 from the circuit is sufficient to operate the extra relay 53. When the relay 53 is operated its armature 76 comes into engagement with its front contact thereby short circuiting the supervisory lamp 44 and the resistance 75 in multiple thus providing enough increase in current in the circuit to light the lamp 64 at the routing clerk's 60 position. At the same time the armature 56

of the extra relay 53 closes a circuit for the lamp 54 at the operating position and the lamp 54 is illuminated and serves as a warning to the operator not to release the line. From the indication given by lamp 64, the routing 70 clerk is informed as to which operator is working on the line and the routing clerk can then dispatch the filed message to the correct operator before the line is released.

It should be noted that the lamp 64 remains 75 illuminated only while the push button 71 is depressed for as soon as the routing clerk releases the push button 71 the resistance 72 is reinserted into the circuit of the lamp 64 and the current is again insufficient to illuminate this lamp. However, the lamp 54 remains 80 illuminated until extinguished by the operator, thus serving as a guide to the messenger. As soon as the messenger has delivered 85 the message to the operator, one may extinguish the lamp 54 by depressing the push button 55.

The routing clerk can depress button after 90 button to obtain information for the messengers only one lamp 64 in the operator group being lighted at a time. The speed at which the system can be operated is dependent only on the routing clerk.

Although the description is given in connection with apparatus as applied to a telephone concentration unit, it will be clear to those skilled in the art that it is equally applicable to other signalling systems, such as telegraphy and simplex printer concentration units which permit the grouping of a 100 large number of underloaded circuits in front of a smaller number of operators.

It will further be clear to those skilled in the art that many departures from the form and details of the embodiment of the invention herein disclosed may be made without departing from the spirit of the invention, the same being herein shown solely for the purpose of clearly illustrating one specific embodiment of the invention.

Having thus illustrated and described one particular embodiment of my invention, what I wish to claim is:—

1. In a switchboard having a plurality of operators' positions, a routing clerk's position and a plurality of subscribers' lines, a plurality of devices at said routing clerk's position for indicating which of said lines are busy and means at said routing clerk's position for indicating which operator is 115 working on any line indicated as busy.

2. In a switchboard having a plurality of operators' positions, a routing clerk's position and a plurality of subscribers' lines, a plurality of devices at said routing clerk's position for indicating which of said lines are busy and manually controllable means at said routing clerk's position for indicating which operator is working on any line indicated as busy.

3. In a switchboard having a plurality of operators' positions, a routing clerk's position and a plurality of subscribers' lines, a plurality of devices at said routing clerk's position for indicating which of said lines are busy, means at said routing clerk's position for indicating which operator is working on any busy line and means at said operator's position for indicating to said operator not to release her line. 10
4. In a switchboard having a plurality of operators' positions, a routing clerk's position and a plurality of subscribers' lines, a plurality of devices at said routing clerk's position for indicating which of said lines are busy, means at said routing clerk's position for indicating which operator is working on any busy line, means at said operator's position for indicating to said operator not to release her line and manually operable means at said routing clerk's position for controlling both of said means. 15
5. In a switchboard having a plurality of operators' positions, a routing clerk's position and a plurality of subscribers' lines, a plurality of devices at said routing clerk's position for indicating which of said lines are busy, means at said routing clerk's position for indicating which operator is working on any line indicated as busy, means at said operator's position for indicating to said operator not to release her line and manually operable means at said operator's position for controlling said last mentioned means. 20
6. In a switchboard having a plurality of operators' positions, a routing clerk's position and a plurality of subscribers' lines, a plurality of devices at said routing clerk's position for indicating which of said lines are busy, means at said routing clerk's position for indicating which operator is working on any line indicated as busy, means at said operator's position for indicating to said operator not to release her line, manually operable means at said routing clerk's position for controlling both of said means and manually operable means at said operator's position for controlling said second mentioned means. 25
7. In a switchboard having a plurality of operators' positions, a routing clerk's position and a plurality of subscribers' lines, a plurality of devices at said routing clerk's position for indicating which of said lines are busy and means whereby a signal may be transmitted from the routing clerk's position to any operator working on a busy line. 30
8. In a switchboard having a plurality of operators' positions, a routing clerk's position and a plurality of subscribers' lines, a plurality of devices at said routing clerk's position for indicating which of said lines are busy, means whereby a signal may be transmitted from the routing clerk's position to any operator working on a busy line and 35
- means responsive to said first mentioned means for indicating at said routing clerk's position which operator is working on said line. 40
9. In a switchboard having a plurality of operators' positions, a routing position and a plurality of subscribers' lines, a plurality of lamps at said routing clerk's position for indicating which of said lines are busy, a key at said routing clerk's position individual to each of said lines for transmitting a signal to the operator working on said line and a lamp at said operator's position responsive to the operation of said key for indicating to said operator not to release her line. 45
10. In a switchboard having a plurality of operators' positions, a routing position and a plurality of subscribers' lines, a plurality of lamps at said routing clerk's position for indicating which of said lines are busy, a key at said routing clerk's position individual to each of said lines for transmitting a signal to the operator working on said line, a lamp at said operator's position responsive to the operation of said key for indicating to said operator not to release her line and a lamp at said routing clerk's position responsive to the operation of said key for indicating at said routing clerk's position which operator is working on said line. 50
